INVENTOR.

Edward J. Casper

BY *Arnold C. Thompson*
ATTORNEY

UNITED STATES PATENT OFFICE

EDWARD J. CASPER, OF NEW YORK, N. Y.

CLIP

Application filed February 6, 1930. Serial No. 426,215.

This invention relates to clips and particularly to devices of this kind for use in connection with the caps of fountain pens, pencils and the like; and the object of the invention is to provide an improved means for attaching the clip to one wall of the tubular cap to provide a secure and positive mounting of the clip in connection with its support and also to reinforce that part of the support through which the securing means passes; a further object being to provide a means of attachment for clips of the class specified, which will prevent injury or destruction to the cap or support in the operation of riveting or spinning the coupling pins; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a cap showing one of my improved clips coupled therewith.

Fig. 2 is a partial, sectional view of the cap shown in Fig. 1 showing the coupling means mounted in connection therewith, prior to securing the clip in position.

Fig. 3 is a view similar to Fig. 1 showing the clip attached.

Fig. 4 is a perspective, detail view of a modified form of coupling means which I employ; and,

Fig. 5 is a section on the line 4—4 of Fig. 1. In the drawing, I have shown for the purpose of illustrating one use of my invention, a tubular closure cap 10 such as is commonly employed in connection with fountain pens, pencils or combined pencils and fountain pens, one end of the cap being closed as seen at 11. At 12, I have shown a clip of more or less conventional form, which is secured to the cap by my improved coupling means, it being understood at this time that any desired form and construction of clip may be

employed, the one shown having a ball end 13, a spring shank 14 and an attaching plate 15 provided with spaced apertures 16. In practice, the wall of the cap 10 is provided with spaced apertures 17, the centers of which correspond with the centers of the apertures 16 in the clip 12, which are of greater diameter than the apertures 16 so as to receive bushings 18.

In practice, a U-shaped coupling member 19 is employed, the crosshead of which is arranged upon the inner face of the wall of the cap 10 and the ends 20 project outwardly through the apertures 17 in said wall. The diameters of said pins correspond to the size of the apertures 16 in the clip 12 so as to fit snugly therein.

By providing the relatively large apertures 17, the U-shaped coupling or mounting member 19 or the pin ends 20 thereof may be freely passed through said apertures after which the bushings 18 are passed downwardly over the pin ends 20 and placed in the aperture 17, the bushings preferably fitting snugly in said apertures, and may, if desired, be forced therein under slight pressure, care being taken not to split or otherwise destroy the cap 10.

After the bushings have been mounted in position, the attaching plate 15 of the clip 12 is arranged in position by passing the pin ends 20 through the apertures 16 after which the protruding ends of said pins may be riveted, spun or otherwise upset to form heads 20a to securely retain the clip 12 in connection with the cap 10.

It will be understood that a mandrel or other tool such as indicated at 10a in Fig. 2 of the drawing, is employed to support the member 19 in position, and to back off said member in the operation of riveting or offsetting the protruding ends of the pins 20. In this operation, the thrust will be taken up by the bushings 18 thus preventing injury to the cap 10, and at the same time, the bushings 18 serve to reinforce and strengthen that part of the cap in connection with which the coupling or mounting member 19 is arranged. After the clip has been secured in position, a short tube 21 may

be arranged in the closed end portion of the cap 10, said tube having a longitudinal groove 22, note Figs. 3 and 5, to receive the crosshead of the member 19. It will be understood that the use of the tube 21 is optional.

In Fig. 4 of the drawing, I have shown a slight modification in the form of the coupling member employed. In this construction, the coupling member 23 also of U-shaped form is employed, and the projecting pins 24 forming the side arms of said coupling correspond to the pins 20, but instead of employing the bushings 18, enlarged collars 25 are arranged at the base of the pins 24 and adjacent the crosshead of the device to form the equivalent of said bushings, the collars fitting in the apertures 17 as will be apparent. It will be understood that other changes in and modifications of the construction herein shown and described may be made within the scope of the appended claims, without departing from the spirit of my invention or sacrificing its advantages.

Having fully described my invention, what I claim as new and desire to secure by Letters Patent, is:—

1. In a clip of the class described adapted to be secured to a suitable support, the attached end of the clip having spaced apertures, and said support having corresponding apertures of greater diameter than those in said clip, a U-shaped coupling body, the pin ends of which are passed outwardly through the apertures in said support and through the apertures in said clip, and means arranged in the apertures of said support to reinforce the same and to take up the thrust in heading the protruding ends of the pins over said clip in securing the clip to said support.

2. In a clip of the class described adapted to be secured to a suitable support, the attached end of the clip having spaced apertures, and said support having corresponding apertures of greater diameter than those in said clip, a U-shaped coupling body, the pin ends of which are passed outwardly through the apertures in said support and through the apertures in said clip, means arranged in the apertures of said support to reinforce the same and to take up the thrust in heading the protruding ends of the pins over said clip in securing the clip to said support, said means comprising bushings arranged upon the pin ends of said coupling.

3. In a clip of the class described having spaced apertures at the attached end portion thereof, a coupling member having spaced pins adapted to pass through the spaced apertures of said clip and headed over the clip to secure the same in position, said coupling including means for anchoring the same to the supporting body of said clip

and to reinforce that part of the supporting body through which the coupling passes.

4. In a clip of the class described having spaced apertures at the attached end portion thereof, a coupling member having spaced pins adapted to pass through the spaced apertures of said clip and headed over the clip to secure the same in position, said coupling including means for anchoring the same to the supporting body of said clip and to reinforce that part of the supporting body through which the coupling passes, and to provide an all metallic body in alignment with the pins to take up the thrust in the operation of heading said pins and to prevent injury to the supporting body.

5. The combination with a tubular cap of the class described, of a supporting clip, the attached end of the clip having spaced apertures, and one wall of said cap having correspondingly spaced apertures of greater diameter than those of said clip, a U-shaped coupling member, the crosshead of which is arranged upon the inner surface of the wall of the cap bridging the apertures therein, and the pin ends of said coupling member passing freely through the apertures of the cap and fitting snugly in the apertures of said clip, the protruding ends of said pins being headed over the clip to secure the same to said cap, and means arranged on said pins within the apertures in said cap to reinforce said cap and to take up the thrust in heading the pins of said coupling member.

6. The combination with a tubular cap of the class described, of a supporting clip, the attached end of the clip having spaced apertures, and one wall of said cap having correspondingly spaced apertures of greater diameter than those of said clip, a U-shaped coupling member the crosshead of which is arranged upon the inner surface of the wall of the clip bridging the apertures therein, the pin ends of said coupling member passing freely through the apertures of the cap and fitting snugly in the apertures of said clip, the protruding ends of said pins being headed over the clip to secure the same to said cap, means arranged on said pins within the apertures in said cap to reinforce said cap and to take up the thrust in heading the pins of said coupling member, said means comprising bushings insertable onto the pins of said coupling member prior to placing the clip thereon.

7. The combination with a tubular cap of the class described, of a supporting clip, the attached end of the clip having spaced apertures, and one wall of said cap having correspondingly spaced apertures of greater diameter than those of said clip, a U-shaped coupling member the crosshead of which is arranged upon the inner surface of the wall of the clip bridging the apertures therein, the pin ends of said coupling member passing

freely through the apertures of the cap and fitting snugly in the apertures of said clip, the protruding ends of said pins being headed over the clip to secure the same to said cap, means arranged on said pins within the apertures in said cap to reinforce said cap and to take up the thrust in heading the pins of said coupling member, said means comprising bushings insertable onto the pins of said coupling member prior to placing the clip thereon, and a tubular body arranged within the cap and having a groove to receive the cross-head of said member.

8. The combination with a tubular cap of the class described and a mounting clip therefor, of means for securing said clip to the cap, comprising a coupling member having ends adapted to be passed outwardly through the wall of the cap and through said clip, the protruding ends of said member being headed to retain the clip in connection with the cap and means arranged in the wall of the cap where said member passes therethrough for reinforcing said cap and to take up the thrust in heading said coupling member.

9. The combination with a tubular cap of the class described and a mounting clip therefor, of means for securing said clip to said cap, said means comprising a **U**-shaped coupling member, the end portions of which are adapted to be passed outwardly through the wall of the cap and through said clip, the protruding ends of said member being headed to retain the clip in connection with said cap, and bushings arranged on the ends of said member where they pass through the wall of said cap.

10. The combination with a cap of the class described and a clip attached to the cap by a coupling member passed through the wall of the cap and said clip, of means for bushing that part of the wall of the cap through which the coupling member passes.

In testimony that I claim the foregoing as my invention I have signed my name this 5th day of February, 1930.

EDWARD J. CASPER.
